UNITED STATES PATENT OFFICE.

RAY L. STOKELY, OF FLORAL PARK, NEW YORK, ASSIGNOR TO BELL TELEPHONE LABORATORIES, INCORPORATED, OF NEW YORK, N. Y., A CORPORATION OF NEW YORK.

TELEPHONE-EXCHANGE SYSTEM.

Application filed July 14, 1927. Serial No. 205,541.

This invention relates to telephone exchange systems and particularly to improvements in message registration on party lines.

According to this invention, a party line subscriber, in order to make a revertive call, sets a train of switches to seize a revertive ringing device whereupon an operator is signaled. The operator listens in and, on hearing the parties converse, manipulates a key to cause the operation of the proper message register.

The invention is illustrated in Figs. 1 and 2 of the drawing which disclose an automatic telephone system employing switches of the step-by-step type. Fig. 1 shows a party line, a line finder and first and second selector switches, and an operator's position schematically. Fig. 2 illustrates a third selector schematically and also shows a special selector in detail and a revertive ringing machine.

Where some party lines in automatic systems are provided with individual message registers for charging the calls, distinction must be made between revertive calls from these lines and revertive calls from flat rate lines. On a revertive call by a flat rate line the calling party line is extended over line finder F through selectors S, S¹, S² and S³ to the code ringing device S⁴. The calling subscriber then replaces his receiver on the switchhook whereupon the ringing device S⁴ applies ringing current to the party line to ring first the called subscriber's bell and then the calling subscriber's bell. These bells are rung alternately until the called subscriber answers. In case the called subscriber does not answer the calling party may release by again removing his receiver from the switchhook and replacing it. On these calls, however, the apparatus has no way of distinguishing between the answer of a called subscriber and the second removal of the receiver by the calling subscriber for the purpose of causing restoration. Accordingly, it has been customary to require a subscriber on a message rate party line to call an operator if he wishes to converse with another party on the same line.

The present system is arranged so that the subscriber on a message register party line may make a revertive call in the same manner that he makes a direct call, namely, by dialing a code which will extend his line to the ringing machine. As soon as he replaces his receiver on the switchhook after having

done this, a signal is given to an operator who merely listens in on the connection and when she hears the parties conversing, she operates a key which reverses the current over the connection to prepare for the operation of the calling subscriber's message register.

The switches S, S¹ and S² are of the well known two-movement step-by-step type with such modifications as are necessary for the purpose of the present invention. The trunk circuit between the finder F and the first selector S is of a type shown and described in detail in my copending application Serial No. 205,540, filed July 14, 1927.

The switch S³ is a single movement rotary step-by-step switch having a bank of terminals 217. The ringing device S⁴ comprises a rotary step-by-step switch connected to the terminals of the bank 217 in such a way as to cause ringing current of different codes to be sent back over a calling party line.

A detailed description will now be given of the manner in which the system operates. Assume that the subscriber at station 101 wishes to converse with the party at station 102 on the same line 100. The initiation of the call causes the line finder F to operate and seize the calling line whereupon the calling subscriber transmits impulses to position the selectors S, S¹ and S² to extend the calling line to the selector switch S³. When the switch S³ is seized a circuit is completed from battery, through the right winding of relay 204, right normal contact of relay 200, inner upper back contact of relay 201, thence over the ring side of the connection through the subscriber's line and returning over the tip side of the connection through the upper back contact of relay 201, normal left contact of relay 200, left winding of relay 204 to battery. Relay 204 operates and closes an obvious circuit for the slow releasing relay 207. Relay 207 at its left contact grounds the sleeve conductor 224 to hold the extended connection.

The last series of impulses, delivered to the switch S³, causes the successive release and operation of relay 204. On the first release of the relay a circuit is closed from ground, through the back contact of said relay, inner right contact of relay 207, normal contacts of the spring combination 210, winding of slow-release relay 208, winding of the rotary stepping magnet 212 to battery. Relay 208 operates and shifts the stepping cir-

cuit so that it leads through the armature and front contact and the winding of said relay. The magnet 212 steps the brushes 225 to 228 inclusive on the first set of terminals in the bank 217. For each succeeding impulse the brushes are advanced one set of terminals. Assume that the last digit is represented by a single impulse whereupon the brushes 225 to 228 inclusive are positioned on the first set of terminals in the bank.

Following the transmission of the last digit the calling subscriber replaces his receiver on the switchhook permitting the release of relay 204. Since the slow-releasing relay 208 releases after an interval following the transmission of the last impulse and since the relay 207 maintains its armatures following the release of relay 204 a circuit may now be traced from ground, through the back contact of relay 204, front contact of relay 207, back contact of relay 208, left contact of relay 205, brushes 226 and 225 and the connected terminals, conductor 229, through the winding of relay 201 to battery. The grounded conductor 229 is also extended through the contact and winding of relay 203, conductor 230, through the switches S^2 , S^1 and S , through the contact and winding of magnet 108 to battery. The manner in which battery potential is connected to the switch S is disclosed and described in my copending application above mentioned Serial No. 205,540, filed July 14, 1927. Relay 203 operates and locks through its left front contact to the grounded sleeve conductor 224. Relay 201 also energizes and connects the calling subscriber's line to the ringing equipment. Relay 201 at its inner lower contact completes a substitute holding circuit for slow-relay 207 to maintain the connection. Relay 201 also completes a circuit from battery, through the winding of relay 213, contact of relay 201, interrupter 216 to ground. Each time the interrupter closes, relay 213 operates and closes a circuit for the stepping magnet 215 which moves the brushes 218 to 222 inclusive from position to position.

When the switch S^4 reaches position 5 a circuit is closed from ground through brush 220, conductor 231, contact of relay 201, contact and winding of relay 202 to battery. Relay 202 locks through its winding and front contact, outer back contact of relay 205 to ground at the front contact of relay 207. In positions 6 and 9 of the switch S^4 a circuit is closed from ground, through the brush 220, brush 228, upper lower contact of relay 202, winding of relay 209 to battery. Relay 209 operates and connects the ringing generator in a circuit through the front contact of the same relay, left winding of relay 205, back contact of relay 206, inner upper front contact of relay 201, to the ring side of the subscriber's line. The tip side of the line is connected through the upper front contact of

relay 201, and the back contact of relay 206 to ground. While the switch S^4 is in positions 8 and 9, a circuit is closed from ground, through the brush 221, thence over brush 227, upper contact of relay 202, winding of relay 206 to battery. Relay 206 operates and reverses the connection of the generator and ground to the tip and ring conductors of the line. Thus, during two positions of the switch the bell at one substation is rung and during the next two positions the bell at the other substation is rung. This code is repeated periodically as the switch continues its rotation.

When the called party answers by removing his receiver the ringing relay 205 operates in the well known manner and opens the circuit for relay 201. Relay 205 locks in a circuit from battery, through its right winding and contact to ground at the contact of relay 207. Relay 205 also unlocks relay 202 which releases relays 206 and 209. The relay 201 disconnects the ringing equipment and reconnects the relay 204 to the subscriber's line. Relay 204 operates and recloses the holding circuit of relay 207. Relay 201 in releasing opens the circuit of relay 213 to prevent further stepping of the switch S^4 .

When the relay 205 operates a circuit is completed from battery, through the signal lamp 111, right contact of relay 203, outer left contact of relay 200, outer right front contact of relay 205, to ground at the front contact of relay 207. The operator at position O, observing the lamp 111, knows that a retractive call is being made. She inserts the plug of her cord circuit into jack 109 and listens in on the connection. When she hears the parties conversing she knows the call has been successful and proceeds to charge the calling subscriber by operating the key 110. The key 110 completes a circuit from battery, through the sleeve of the jack 109, contacts of said key, conductor 112, right winding of relay 200 to ground. Relay 200 operates and locks in a circuit from battery, through its left winding and outer left front contact, outer right front contact of relay 205 to ground at the front contact of relay 207. Relay 200 reverses the direction of current flow through the windings of relay 204 to the tip and ring conductors of the line. This reversal of current causes the operation of the polarized relay 106 in the trunk circuit between the finder F and the selector S. Relay 106 in operating closes a circuit for relay 107.

When the conversation is over and the subscribers replace their receivers on the switchhooks, relay 204 releases in turn releasing relay 207. Relay 207 completes a circuit from ground, through its outer right back contact, closed contacts of the combination 210, winding of the release magnet 211 to

battery. Magnet 211 restores the switch S^3 to normal. Relay 207 also removes ground from conductor 224 causing the release of switches S^2 , S^1 and S and F .

- 5 3 During the release of the trunk circuit between the finder F and the selector S , a circuit is completed from battery, through the contact of relay 107, thence over conductor 113, through the front contact of relay 105, 10 assuming this relay to be operated, through a brush on the finder switch F , and the winding of the message register 104 to the opposite pole of battery and ground. The register 104 thus operates, charging the call to the 15 subscriber of station 101.

It will be obvious by inspecting the switch S^4 that different codes for signaling the party lines may be selected by setting the switch S^3 on different terminals in its bank 217.

- 20 20 The manner in which a party line is tested to determine which party initiated the call is fully described in the patent to Taggart et al. No. 1,513,351, granted October 28, 1924.

What is claimed is:

- 25 1. In a telephone system, a party line, a message register for each party, a revertive ringing machine, selector switches controlled by a subscriber on the party line for seizing said machine when a revertive call is made, 30 an operator's position, means for signaling the operator if a connection is extended to said machine, and means controlled by the operator for selectively operating said message registers.
- 35 2. In a telephone system, a party line, a message register for each party, a revertive ringing machine, selector switches controlled by a subscriber on the party line for seizing said machine when a revertive call is made, 40 means controlled by said machine for signaling the parties on said line, an operator's position, means responsive to the seizure of said machine for signaling the operator, and

means under control of the operator for selectively operating said registers. 45

3. In a telephone system, a party line, a message register for each party, a revertive ringing machine, selector switches controlled by a subscriber on the party line for seizing said machine when a revertive call is made, 50 an operator's position, means controlled by one of said selectors responsive to the seizure of said machine for signaling the operator, means at said position for listening in on the connection, and means controlled by the 55 operator for actuating said registers.

4. In combination, a party line having individual message registers, a revertive signaling device, automatic switches controlled by the subscribers for extending said line to 60 the signaling device, means controlled by the calling subscriber's switchhook for rendering said signaling device effective to signal both the calling and called parties, an operator's position, means responsive to the 65 seizure of said device for signaling the operator, and means controlled by the operator for actuating said registers.

5. In combination, a party line having individual message registers, a revertive signaling device, automatic switches controlled by the subscribers for extending said line to 70 the signaling device, means controlled by said device responsive to the replacement of the calling subscriber's switchhook for sending code signals to both calling and called 75 substations on the party line, an operator's position, a lamp at said position lighted in response to seizure of the signaling device, and means controlled by the operator for 80 reversing the flow of current over the extended connection to cause operation of one of said registers.

In witness whereof, I hereunto subscribe my name this 8 day of July, A. D. 1927.

RAY L. STOKELY.
